UNITED STATES PATENT OFFICE.

GEORGE CUFF, OF POYNETTE, WISCONSIN.

WINDMILL OPERATING MECHANISM.

1,143,811.

Specification of Letters Patent. Patented June 22, 1915.

Application filed April 24, 1913. Serial No. 763,293.

To all whom it may concern:

Be it known that I, GEORGE CUFF, a citizen of the United States, residing at Poynette, in the county of Columbia and State of Wisconsin, have invented a new and useful Windmill Operating Mechanism, of which the following is a specification.

My invention relates to windmills for operating water pumps or other machinery.

One of the main objects of the invention is to overcome the usual wasting of time and power in windmills, due to the fact that the wind wheel rotates a crank and the latter operates a rod or pitman by means of which a single-acting pump or like device is put into actual service only during one-half of each revolution of the crank.

Also other objects are attained, as will hereinafter be fully described and pointed out in the claims; reference being had to the accompanying drawings, in which:—

Figure 1 is a side elevation of my improved windmill applied to a single-acting well-pump. Fig. 2 is a portion of what is shown in Fig. 1 with one of the wheels 19 omitted. Fig. 3 is an enlarged partly sectional view on the line *a—a* Fig. 1 with some parts omitted. Fig. 4 is a section on the line *b—b* Fig. 1 showing the rear side 30 of the saddle frame 6. Fig. 5 is a further enlarged top view of the frame 6 with its cap removed. Fig. 6 is a top view of the cap removed from Fig. 5, and the sheave mounted therein.

Referring to the drawings by reference numerals, 1 designates the platform covering a well, and upon which a single-acting pump 2 is arranged for pumping water from the well. Upon said platform, or adjacent the same, is erected the tower 3 of the windmill. The top of the tower is provided with a metallic head 4, in which is journaled a tubular downward extension 5 of a saddle casting or frame 6 adapted to 45 rotate about a vertical axle central with the tower. The tube 5 may extend as far down in the tower as desired so as to prevent bending of the pump operating rod 7 which reciprocates in the tube and is connected at 50 8 with the piston rod 9 of the pump.

Clamped by screws 10 in the split rear side of the frame 6 are the rods 11 of the vane 12 of the mill. The upper portion of the frame 6 is provided with four vertical

slots 13, (see Fig. 5) in which are guided 55 four ribs of a crosshead 14, which is fixed on the top end of the operating rod 7, and is operated by a bifurcated pitman 15, which has its upper ends pivoted at 16 to the crosshead and its lower ends provided with anti-friction rollers 17, (best shown to the left in Fig. 3) which are inserted in concentric grooves 18 of two wheels 19. Said wheels 19 are fixed one at each end of a horizontal shaft 20, at the middle of which is fixed a 60 worm-gear 21, rotating in a slot 22 in the front side of the frame 6. The shaft is journaled in forwardly open bearings 23 (best shown in Figs. 2 and 3) projecting one from each side of the frame and finally 65 closed by inserted journal blocks 24, which are held in place by journal boxes 25, which encircle the parts 23 and 24 and constitute the integral hangers of a secondary frame 26. In said frame 26 is journaled a shaft 70 27, carrying at one end a worm-screw 28, which is permanently engaged with the worm gear 21, and at the other end a wind wheel 29.

On the top of the frame 6 is secured by 80 screws 30 a cap 31 having an aperture 32 and a space 33 in which a sheave 34 is mounted. Guided over said sheave is a chain or other flexible element 35, which has one end secured at 36 to the front end of the 85 frame 26 and its other end passed down through the frame 6 and the tube 5 and secured either to a cleat like 37 on the pumping rod, or to a winding drum 37^x mounted on a post 38 and provided with a crank 39 90 and ratchet teeth 40 in which a weighted ratchet dog 41 is arranged to engage and hold the frame 26 in horizontal position, or to hold said frame in the vertical position 95 shown in dotted line in Fig. 1 with the windwheel edgewise to the wind and above the top of the frame 6.

Extending from the lug 42 of the frame 26, and slidable in the aperture 32 in the 100 cap 31, is a rod 43, having its upper end provided with a nut 44 and a spring 45 partly compressed between the nut and the cap 31, said spring serving as a cushion when the wind wheel is suddenly lowered 105 into active position. At the lower end of the rod is a similar spring 46 with a washer 47 placed loosely at the top of it. This

spring serves as a cushion against the cap 31 when the wind-wheel is suddenly thrown upward out of the wind.

Turning again to the wheels 19, it will be noted that adjacent the inner curve of the groove 18 is a circular row of catches 49, pivoted at 48 and normally held yieldingly in a radial position by a circular spring 50, which contacts with a flattened point or face of each catch. Each of said catches can, however, swing only in one direction on its pivot, it being obstructed in the other direction by a lug 51 on the wheel (as best shown in Fig. 1).

In the operation of the device, when the wind wheel turns the worm screw and the worm gear, the wheels 19 will rotate in the direction indicated by an arrow in Fig. 1 and thus in each wheel one of the catches will carry the roller 17 from the lowest to the highest position in the groove 18 and thereby pull the pump piston its full stroke upward. As soon as the roller 17 is carried slightly beyond the dead-center in the top of the wheel 19, the weight of the cross head 14 and the pump rod pulls the roller instantly down to its lowest position in the groove 18, the catches 49 yielding before it, and upon reaching said lowest position the catch nearest behind it almost at once engages the roller and causes the pitman 15 to impart the next upward stroke of the pump piston, and so on, the pump is kept in practically continuous water-raising action, and can thus pump nearly twice as much water in a given time as it would pump with the ordinary crank action well known in this art.

What I claim is:—

1. In a wind mill mounted in a suitable tower and frame work, a vertically reciprocating rod, a pitman connected with the rod, a wheel having pivoted supports, catches arranged to engage the pitman to raise it while moving upward half a turn of the wheel, said catches being yieldable away from their supports to permit the pitman to return quickly downward ahead of the turning of the wheel to the lowest position relative to the wheel, and a power transmitting wheel operatively connected with the wheel having the catches.

2. In a wind mill, the combination of a tower, a frame mounted to rotate about a vertical axis at the top of the tower and having a central opening, a rod extending down through said opening, a cross-head secured to the top of the rod and guided to slide vertically in the frame, a pitman having its upper end pivoted to the crosshead and its lower end provided with a horizontally disposed roller, a horizontally disposed shaft mounted in the frame, a wheel fixed on the shaft and having in one side a concentric groove for the roller of the pit-

man to move in, catches pivoted on the wheel adjacent the groove so as to engage the roller, said wheels having lugs to prevent the catches from swinging in more than one direction, and a power transmitting wheel operatively connected with the shaft to turn it.

3. In a wind mill, the combination of a tower, a frame mounted to rotate about a vertical axis at the top of the tower and having a central opening, a rod extending down through said opening, a cross-head secured to the top end of the rod and guided to slide vertically in the frame, a pitman having its upper end pivoted to the cross head and its lower end provided with a horizontally disposed roller, a horizontally disposed shaft mounted in the frame, a wheel fixed on the shaft and having in one side a concentric groove for the roller of the pitman to move in, catches pivoted on the wheel adjacent the groove so as to engage the roller, said wheels having lugs to prevent the catches from swinging in more than one direction, and a power transmitting wheel operatively connected with the shaft to turn it, and means for holding the catches yieldingly against the lugs.

4. In a wind mill, the combination of a tower, a frame mounted to rotate about a vertical axis at the top of the tower and having a central opening, a cross-head mounted to slide up and down in the frame, a working rod extending from the cross head centrally down through the frame and the tower, a pitman having its ends bifurcated into two upper and two lower arms, the upper arms being pivoted to two opposite sides of the cross-head, and the lower arms being each provided with a laterally projecting antifriction roller, a shaft journaled in the frame, two wheels fixed on the shaft, each of said wheels having in one side a concentric groove for one of the antifriction rollers to move in, a series of concentrically arranged lugs on each wheel adjacent the groove, a spring-held catch pivoted near each lug so as to be supported in one direction by the lug and when thus supported adapted to engage the roller and carry it and the pitman upward during half a revolution of the wheel, a power transmitting wheel, and operative connection between it and said shaft.

5. In a wind mill and mounted in a suitable frame and tower, a power-transmitting shaft and a worm-screw fixed on same, a worm-wheel driven by said worm-screw, a shaft fixed in the worm-wheel, a wheel fixed on each end of the worm-wheel shaft, and having in one side a concentric groove and near the groove a series of lugs, catches pivotally mounted near the groove and by said lugs allowed to turn in but one direction; a pitman having two downward arms, each

arm provided with a roller fitting in one of the concentric grooves, a cross-head guided in the framework to slide up and down therein and pivotally secured to the pitman, 5 a working rod operated by the cross-head and adapted to operate working machinery at the base of the wind mill.

In testimony whereof I affix my signature, in presence of two witnesses.

GEORGE CUFF.
